COMBINED SHOULDER CORD AND HOOD

Selig J. Frank, San Antonio, Tex., assignor to Sol Frank Uniforms, Inc., San Antonio, Tex., a corporation of Texas

Filed May 20, 1963, Ser. No. 74,968

Term of patent 14 years

(Cl. D3—32)

Fig. 1

FIG. 1 is a top plan view of a combined shoulder cord and hood showing my new design; and

FIG. 2 is a side elevational view; and

FIG. 3 is a bottom plan view.

I claim:

The ornamental design for a combined shoulder cord and hood, as shown.
